JOHN FRANK BUBNA LITIC, OF GRANTWOOD, NEW JERSEY, ASSIGNOR TO FREDERICK H. MINARD, OF NEW YORK, N. Y.

ADVERTISING SIGN

Application filed March 13, 1928. Serial No. 261,224.

The present invention relates to advertising signs and more particularly to luminous signs designed to effect an optical illusion. In some types of signs wherein illuminating means are applied to the sign in sequence or alternately, generally known as animated advertising, a translucent screen with advertising matter on each side is employed, and the illuminating means is disposed behind the screen. The principal object of this invention is to apply the advertising matter or indicia on the front of a screen of this type and so regulate the relative illumination of the front and rear of the screen that a series of contrasting effects are transmitted to the observer. The invention utilizes the property of colored pigments to appear differently when viewed by reflected light than when viewed by light transmitted therethrough. The invention will be more fully understood from the following description taken in connection with the accompanying drawings, in which

Fig. 1 represents one form of the invention, as it appears without illumination of the rear of the screen;

Fig. 2 represents the sign shown in Fig. 1 when the rear is illuminated to a certain degree;

Fig. 3 represents the same sign, the intensity of the light behind the screen being greater than that of the light employed to produce the effect shown in Fig. 2; and

Fig. 4 is a side view of the screen showing one arrangement of the illuminating means.

Referring to the drawings, a screen 10 of paper, glass or other suitable material is coated or otherwise colored with a dark pigment as shown at 11, such as, however, to leave the colored screen translucent. It has been found in practice that a dark grey is suitable for the purpose, and in order to simplify the description of the operation of the device the colored portion 11 will be referred to hereinafter as grey. It is to be understood, of course, that other colors may be employed with equal effectiveness. Su-

perposed on the colored portion of the screen are letters, designs or other advertising matter 12, of a contrasting color and lighter

than the colored background on which they are painted or printed. A white paint or ink produces effective results, and the advertising matter 12 may be referred to hereinafter as white to simplify the description.

As shown in Fig. 1 letters "AH" appear white on a grey background. This is due to the fact that only reflected light is seen, the illumination of the front of the screen being produced by a lamp 14 (see Fig. 4) in front of the sign or by ordinary sunlight during the day. If the rear surface of the sign is now illuminated and the intensity of the light on the rear surface is properly regulated, the lighter letters on the front of the screen will apparently disappear as indicated in Fig. 2. This result may be obtained by making the quantity and color of the transmitted and reflected light of the grey background 11 equal to the quantity and color of the transmitted and reflected light of the white letters 12. One method of producing the desired intensity on the rear of the screen is shown in Fig. 4, the lamp 13 being so spaced from the screen that the equation referred to above with respect to lamps 13 and 14 is fulfilled to produce the effect shown in Fig. 2.

Suitable energizing means may be provided for the lamps 13, 14 and 15 and where these lamps are electric, this means may be in the nature of an electric circuit, conventionally represented at 16 and adapted for selectively connecting therein the various lamps as by switches 17 and 18. In case of the other types of lamps being used, well known apparatus for obtaining the desired effects may, of course, be used. It will be understood that suitable means may be included in the circuit 16 whereby the throw of the various switches may be made automatic. Owing to the well known character of such devices, it has not been thought necessary to illustrate any specific embodiment thereof with these specifications.

As a further step in producing still another result the lamp 15 may be placed close to the rear of the screen so that the intensity of the light on the rear of the screen is greater than that on the front. Although the letters are white, the constituents of the paint are

solid and more opaque than the material used to produce the colored background and, for this reason, appear darker than the background when the quantity and color of the transmitted and reflected light of the background is greater than the quantity and color of the transmitted and reflected light of the letters to produce the effect shown in Fig. 3.

It will thus be seen that it is possible to color and paint on one side, or in other words the front surface, of a transparent or translucent material suitable designs, letters or other advertising material and vary the intensity of the light on the rear surface of the material, so that at least two and, if desired, three contrasting effects are produced. As a matter of fact the sign may be produced by ordinary printing methods and thus be manufactured at small cost. Instead of employing two lamps at different distances from the rear of the screen the same result may be obtained by inserting a resistance in the lamp circuit and varying the current employed for illuminating the lamp. Or, if desired, means may be employed for moving the lamp towards and away from the screen to vary the intensity of the light on the rear of the screen. The same optical effects may also be produced by having a permanent light behind the screen and increasing or diminishing the light in front. The contrasting effects are obtained by variation of the relative illumination of the front and rear of the screen and this may be obtained in any of numerous ways.

As stated above, it is not intended that the background be limited to a grey color. It has been found, for instance, that a color produced by mixing brown and yellow with a colorless varnish will appear white when the intensity of the light on the rear of the screen is at a predetermined value. It is, therefore, possible to produce a sign which appears to be white when the rear of the screen is illuminated, whereas when light is projected on the front only, the coloring material will stand out in contrast to the uncolored portion of the screen, if the latter is of a translucent and light material such as paper or frosted glass.

The principle utilized in the invention is the property of colored pigments to appear differently when viewed by reflected light than when viewed by light transmitted therethrough. In applying the invention, only the face or front of the screen is colored, as the colors must appear only on the front if to be viewed by both reflected and transmitted light. The colors may be superposed on one another, as already described, but this is not essential as it is within the scope of the invention to apply the different colors to different portions of the front face of the screen without superposing the colors and thus obtain similar results. The invention general-

ly may be practiced by producing on the front of a screen a plurality of portions having different colors with different appearances when viewed by reflected or transmitted light.

Although a preferred form of the invention has been described and illustrated, it is obvious that various combinations of lights and colors may be employed to produce a number of effects, and it is, therefore, not intended that the invention be limited to the specific embodiment shown and described.

What I claim is:

1. The method of producing optical effects in translucent advertising signs which consists in placing indicia on one side only of the sign, said indicia being of the same color as the rest of the sign but of different shades and differing from the rest of the sign in perviousness to light projecting light on said side, and varying the amount of light on the other side of the sign.

2. The method of producing optical effects in translucent signs which consists in placing indicia on one side only of the sign, said indicia being of the same color as the rest of the sign but of different shades and differing from the rest of the sign in perviousness to light, projecting light on said side and varying the amount of light on the other side of the sign to make the quantity and color of transmitted and reflected light of the indicia equal to the quantity and color of transmitted and reflected light of the remainder of the sign.

3. An advertising device comprising a translucent screen having indicia placed on one side only thereof, said indicia being of the same color as, but of a different shade than said screen and of a different perviousness to light than said screen, said screen being capable of reflecting light projected thereon, means for illuminating the other side of said screen and means for varying the amount of light on said other side.

4. An advertising device comprising a translucent screen having indicia placed on one side only thereof, said indicia being of the same color as, but of a different shade than said screen and of a different perviousness to light than said screen, said screen being capable of reflecting light projected thereon, means for illuminating the other side of said screen, and means for varying the light projected on one side of said screen to make the quantity and color of transmitted and reflected light of the indicia equal to the quantity and color of transmitted and reflected light of the remainder of the screen.

5. A device for producing optical effects comprising a translucent sign having a plurality of colored portions of differing optical density, said colored portions being such that when viewed in a certain light they will appear the same and means for varying the

relative illumination of the front and rear of said sign.

6. A device for producing optical effects comprising a translucent sign having a plurality of colored portions of differing optical density, said colored portions being such that when viewed in reflected and transmitted light of intensities of a certain ratio they appear the same and when viewed in reflected and transmitted light of intensities of other ratios they contrast in appearance and means for varying the relative illumination of the front and rear of the said sign.

7. A device for producing optical effects comprising a translucent sign having a plurality of colored portions having differing optical densities, said colored portions being such that when viewed in reflected and transmitted light of intensities of a certain ratio they appear the same and when viewed in reflected and transmitted light of intensities of other ratios they contrast in appearance, illuminating means for one side of said sign and means for varying the intensity of the illumination.

8. A device for producing optical effects comprising a translucent sign having a plurality of colored portions having differing optical densities, said colored portions being such that when viewed in reflected and transmitted light of intensities of a certain ratio they appear the same and when viewed in reflected and transmitted light of intensities of other ratios they contrast in appearance, illuminating means for both sides of said sign and means for varying the intensity of said illuminating means.

9. A device for producing optical effects comprising a translucent sign having a plurality of colored portions of differing optical density and of differing shades of the same color and means for varying the relative illumination of the front and rear of said sign.

10. The method of producing varying optical effects in signs which consists in providing a screen having separate relatively translucent and opaque regions, projecting light of constant intensity on one side of the screen, and with selectively varying intensity upon the opposite sides thereof.

11. The method of producing varying optical effects in signs which consists in illuminating an area of a screen uniformly over one side thereof and transmitting light of selectively varying intensity through the screen from the opposite side in fractional regions only of said screen.

In testimony whereof, I have signed my name to this specification this 9th day of March, 1928.

JOHN FRANK BUBNA LITIC.
